UNITED STATES PATENT OFFICE.

MILTON O. THOMPSON, OF BOSTON, MASSACHUSETTS, ASSIGNOR, BY MESNE ASSIGNMENTS, OF ONE-HALF TO DEXTER B. HILL, OF NEWTON, MASSACHUSETTS.

DESIGN FOR AN EGG-BEATER.

55,340.

Specification for Design.

Patented May 25, 1920.

Application filed May 9, 1919. Serial No. 296,005. Term of patent 7 years.

To all whom it may concern:

Be it known that I, MILTON O. THOMPSON, a citizen of the United States, residing at Boston, in the county of Suffolk and State of Massachusetts, have invented a new and original and ornamental Design for Egg-Beaters, of which the following is a specification, reference being had to the accompanying drawing, forming a part thereof.

In the drawing I have shown a perspective view of an egg beater embodying my new design.

What I claim is—

The ornamental design for an egg beater, as shown.

MILTON O. THOMPSON.
